UNITED STATES PATENT OFFICE.

EDWARD C. SUCKERT, OF DETROIT, MICHIGAN..

LOOSE-LEAF LEDGER OR BINDER.

SPECIFICATION forming part of Letters Patent No. 772,847, dated October 18, 1904.

Application filed October 17, 1903. Serial No. 177,389. (No model.)

To all whom it may concern:

Be it known that I, EDWARD C. SUCKERT, a citizen of the United States of America, residing at Detroit, in the county of Wayne and State of Michigan, have invented certain new and useful Improvements in Loose-Leaf Ledgers or Binders, of which the following is a specification, reference being had therein to the accompanying drawings.

10 This invention relates to improvements in temporary binders of the class known as "loose-leaf" ledgers; and its object is to provide a device so constructed that it may be very easily and quickly extended to increase 15 its capacity; and it consists of few parts, making it simple and cheap.

A further object of the invention is to so attach the covers to the back as to make a flat-opening book and so as to prevent the metal 20 parts from contacting the desk or table upon which the book may be placed and also to provide certain other new and useful features, all as hereinafter more fully described, reference being had to the accompanying drawings, in 25 which—

Figure 1 is a plan view of a device embodying the invention, showing the inner side of the same when open. Fig. 2 is an enlarged end elevation of the same; Fig. 3, a transverse 30 section on the line $\alpha\alpha$ of Fig. 1, and Fig. 4 a sectional plan view of the back on the line $\gamma\gamma$ of Fig. 2.

As shown in the drawings, A represents the covers, secured to the back B by providing 35 each cover with a bar 1, which is attached thereto by wrapping around said bar the leather strip, which is attached to the inner edge of the cover and forms the ordinary flexible connection 2 between the cover and back, 40 and gluing the same thereto, said bars being firmly secured by screws 3 to the upwardly-extending side flanges of the back with their lower edges extending below the plane of the back to prevent the metal back from contacting the desk upon which the book may be placed.

The back B consists of two parts, 4 and 5, movable one upon the other, the part 4 being provided with a lip 6 at each end, which is 45 turned up over the end of the part 5 and holds

the parts together, and each part is bent at right angles to form the side flanges 7 of the back, to which flanges the covers are secured, said flanges being extended beyond the bars 1 and turned inward to form eyes 8 at their upper edges. The eyes 8 are cut away at intervals to receive the ends of the binding members 9 and also the adjusting member 10, which members are detachably held in place at one end to extend across the back to the 55 opposite flange through openings provided therefor in the edges of the leaves or other matter to be bound by a rod 11 extending through the eye on the flange and openings 12 in the ends of the binders and adjusting member. This rod 11 is detachably held in place by being bent at right angles at one end to 60 engage a spring-clip 13 on the side flange 7 of the back.

Each binding member 9 consists of two tubular parts of a size to telescope one within the other and curved throughout their length, so that the leaves at the center of the book will be raised higher than those next the covers, thus allowing the leaves to lie much more 75 nearly flat when the book is opened than they could if the binders were straight.

The adjusting member 10 for moving the two parts of the back toward and from each other to increase or decrease the capacity of 80 the binder consists of providing a tubular member 14, secured at one end to the side flange of the back by the rod 11, as described, and a tubular member 15 to receive the tube 14, said telescoping tubes forming a casing for 85 the adjusting-screw 16, which engages the internally-screw-threaded end of the tube 14 and is secured at its opposite end, together with the tube 15, to the side flange of the back opposite that to which the tube 14 is attached 90 by rods 17 extending inward from each end of the binder through the eye 8 on said flange and through an opening in the end of the tube 15 into engagement with a groove 18, formed in a head 19, which fits within the end of said tube. The adjusting-screw and its casing-tube 15 are thus attached to the member 4 of the back to move therewith, the screw being free to turn within said tube, but held from longitudinal movement therein by the engage- 100

ment of the ends of the rods 17 with the groove 18, and a socket 20 is provided in the head of the screw to receive a key 21 for turning the same. These rods 17 are held within 5 the eye 8 with their inner ends engaging the groove by screws 22, inserted in the outer ends of said eye, and these rods also extend through openings 23 in the ends of the telescopic binders to pivotally secure the same to 10 the flange of the member 4 of the back.

To move the ends of the two parts of the back equally, so that the part 5 will not bind in the guides 6, two flat bars 24 and 25, pivotally secured together by a rivet 26 intermediate their ends, are pivotally secured at one end to the parts 4 and 5 of the back by the rivets 27, the bar 24 to the part 4 and the bar 25 to the part 5. At their opposite ends these bars are slotted at 29 longitudinally to 20 receive the rivets 28 on the back, the bar 24 being thus attached at this end to the part 5 and the bar 25 to the part 4, and thus when the back is extended or contracted by turning the adjusting-screw 16 the parts will move 25 freely and easily upon each other as power is applied equally to each end of each part and are limited in their movement by the slots 29, the rivets 28 engaging the outer ends of said slots when the back is fully extended.

30 By securing the covers to the back at a point below the upper edges of its side flanges to which the binders are attached the leaves will lie nearly flat when the book is opened, and by employing the leather-covered bars 1 35 to secure the covers to the back the back is strengthened and at the same time prevented from contacting the table or desk.

The leaves are cut away opposite the adjusting member 10, so that said member will in no 40 way interfere with the movement of the leaves or their insertion or removal, and when the leaves are punched to form openings to receive the binders it is necessary to remove the rod 11 to release the binders before the leaves may be 45 inserted. It is preferable, however, to form these openings in the leaves with a slot-opening through the edge of the leaf, so that by extending the back new leaves may be slipped over the binders without detaching them, the 50 upward curve of these binders, which curve is increased as the back is extended, greatly aiding in inserting these leaves. These slotted leaves are firmly held against removal when the back is again contracted, as it is necessary 55 that there be room to bend or separate their lower corners in order to remove the leaves.

Having thus fully described my invention, what I claim is—

60 1. In combination with a back having side flanges extending at right angles thereto, of bars secured to the outer sides of said flanges with one edge at a distance from the edge of the flanges and the other edge projecting beyond 65 the face of the back, covers, and flexi-

ble strips extending around said bars to cover the same and secured thereto and to the edges of said covers to flexibly unite the covers to the bars.

2. The combination with a back consisting 7c of two parts adjustable toward and from each other, of binders each consisting of two members upwardly curved throughout their length and adapted to telescope one within the other, and means for pivotally connecting one end 75 of each member of each of said binders to the back.

3. The combination of a back consisting of two parts adjustable toward and from each other, flanges on said back extending at right 80 angles thereto and formed with eyes at their edges, a tubular member having an internal screw-thread and provided with an opening, a rod extending through the eye of one flange and the opening in the tubular member to 85 pivotally secure the same to the flange, a tubular casing having an opening near one end and adapted to receive the tubular member, an adjusting-screw in said casing to engage the screw-thread of the tubular member, and 90 provided with a groove near one end, and rods in the eye on the other flange projecting through the openings in the casing and into the groove in the adjusting-screw to pivotally secure the casing to the flange and hold 95 the screw in place.

4. The combination with a back consisting of two parts guided to slide one upon the other, a bar pivotally secured at one end to one part near the end thereof and provided 100 with a slot near its opposite end, a pivot-pin extending through said slot to pivotally secure the end of the bar to the opposite part of the back near the opposite end of the back, a bar pivotally secured at one end to that part 105 of the back to which the slotted end of the other bar is secured and provided with a slot near its opposite end, a pivot-pin extending through said slot to pivotally secure the slotted end of the bar to the opposite part of the back, a rivet to pivotally secure the bars together at their crossing-point, side flanges extending at right angles to the back, and binding members pivotally secured at their ends to said flanges and each consisting of two parts 115 adapted to telescope one within the other.

5. The combination of a back consisting of two parts guided to slide one upon the other; a side flange on each of said parts extending at right angles to the back; binders pivotally 120 secured at their ends to said flanges; bars each pivotally attached at one end to one part of the back near one end thereof and at its opposite end to the opposite part at the opposite end of the back, and pivotally secured together at their point of intersection; and an adjusting member consisting of a tubular casing attached at one end to one of the flanges, an adjusting-screw within said casing, and provided with a socket for the engagement of 130

a key to turn the same, and a tubular member attached at one end to the opposite flange with its opposite end extending within the casing and provided with an internal screw-thread to engage the screw-thread of the adjusting-screw.

6. The combination with covers; of a back consisting of overlapping parts, one part being provided with guide-flanges to engage the other part; side flanges on said parts extending at right angles thereto and formed with eyes at their upper edges, bars each pivotally attached at one end to one part of the back near one end thereof and at its opposite end provided with a slot engaged by a rivet on the opposite part at the opposite end of the back and both pivotally secured together at their points of intersection; an adjusting member consisting of a tubular casing member provided with an opening near one end, an adjusting-screw within said casing having a head

provided with a groove opposite the opening in the casing, and a tubular member to telescope within the casing and provided with an internal screw-thread and an opening near one end; binders each consisting of telescopic tubular parts curved throughout their length and provided with openings in their ends; a rod to extend through the eye on one flange and the openings in one end of the binders and adjusting member; rods within the eye on the opposite flange extending inward from the outer ends thereof and engaging the groove in the head of the adjusting-screw; and screws within the outer ends of said eye to hold said rods thereon.

In testimony whereof I affix my signature in presence of two witnesses.

EDWARD C. SUCKERT.
